attorney.

UNITED STATES PATENT OFFICE.

ALFRED PARKER STOKES, OF ST. HELIERS, JERSEY, CHANNEL ISLANDS.

METHOD OF PRODUCING SUSPENSORY BANDAGES.

Application filed July 14, 1920. Serial No. 396,255.

To all whom it may concern:

Be it known that I, ALFRED PARKER STOKES, a subject of the King of Great Britain and Ireland, residing at 3 Green 5 Street, St. Heliers, Jersey, Channel Islands, have invented new and useful Improvements in Methods of Producing Suspensory Bandages, of which the following is a specification.

10 This invention relates to the manufacture of suspensory bandages for men's use, and consists in a simple method of producing the same from tubular or sleeve-shaped material of the "stockinette" character such 15 as yielded by a circular knitting machine.

In the accompanying drawings, Fig. 1 represents a length of the tubular material folded flat and cut in such a manner as to produce two of the said bandages without 20 waste. Fig. 2 represents one of these portions separated from the other portion. Fig. 3 represents the same piece after being cut along its lower edge and opened out flat. Fig. 4 represents the same piece when in 25 course of application, the material being of such an elastic character as to admit of any of its portions being considerably stretched.

The first operation of dividing the length of flattened tube into two portions a a' may 30 be effected by means of a crank-shaped knife corresponding with the cutting line x in Fig.

1. The portion which remains cylindrical is then severed along the line Y in Fig. 2. Upon being opened out the material assumes 35 a T-form as shown in Fig. 3. The two arms b b are capable of being readily stretched to two or three times their length, and of forming a band adapted to be passed round the

body of the wearer and tied in front. The middle portion c is then passed between the 40 legs, the corners d d are seized, stretched apart, and secured to the front of the band previously referred to.

I claim:

1. The method of producing suspensory 45 bandages, which consists in dividing a knitted tubular body into two like parts consisting each of a relatively longer flat body portion and a relatively shorter tubular portion at each end, then severing the tubular 50 portions substantially symmetrically relatively to the body portion to form strips projecting laterally thereof and then stretching the strips.

2. The method of producing suspensory 55 bandages which consists in cutting a knitted tubular body near its ends substantially at right angle to the body and lengthwise intermediate the cuts to form two like parts defining each a relatively longer flat body 60 portion and a relatively shorter tubular portion, then severing the tubular portion to define two strips extending laterally from the body portion and then stretching the strips.

3. In a method of producing suspensory 65 bandages, the steps which consist in cutting a knitted tubular body near its ends substantially at right angle to the body and lengthwise intermediate the cuts to form two like parts defining each a relatively longer flat body portion and a relatively shorter tubular portion and then severing the tubular 70 portion to define two strips extending laterally from the body portion.

ALFRED PARKER STOKES.
